UNITED STATES PATENT OFFICE.

CHARLES HOWARD WALTER MORRISON, OF LONDON, ENGLAND. ASSIGNOR, BY DIRECT AND MESNE ASSIGNMENTS, TO M. & P. ENTERPRISES LIMITED, OF LONDON, W. 1, ENGLAND, AND WILLIAM HERBERT PEAK, OF LONDON, W. 14, ENGLAND.

ELECTRIC HEATER.

Application filed July 10, 1922. Serial No. 573,955.

To all whom it may concern:

Be it known that I, CHARLES HOWARD WALTER MORRISON, a subject of the King of Great Britain and Ireland, and a resident of 5 London, England, have invented certain new and useful Improvements in Electric Heaters of which the following is a specification.

This invention which relates to improvements in electric heating devices, is suitable for heating small quantities of liquid or semi-liquid substances, tools or other appliances, and also for evaporating volatile chemical compounds as essences, perfumes, 10 or other substances having disinfecting or antiseptic properties, so that by vaporization the said compounds or substances may be more readily disseminated through the atmosphere for hygienic purposes.

20 The device has reference to electric heaters wherein electric resistance elements mounted on a base with a removable cover plate over the terminals are covered by an outer shell shaped with a cup-like cavity disposed over the elements.

According to the present invention there is employed a base on which stands a pair of upright conductive legs carrying detachably between their upper ends the resistance heating element, and a cover with a cup-like depression on its upper surface.

The improved device according to this invention embodies novel construction with facilities for easily detaching and replacing the heating elements, and is illustrated in the accompanying drawings.

Figure 1 is a vertical section, and

Figure 2 a plan view, the metal cover having been removed.

40 The base may be of wood, vulcanite, ebonite, or other insulator, and suitable means are provided for bringing a twin flexible cable through the base for leading the current to the heating elements. The base consists of two pieces, a top part 1, which holds the elements and their supports and a bottom cover 1^a which forms a protection for the terminals of the apparatus. These two parts are fixed together 45 by screws or other suitable means.

The heating elements 6 consist of high resistance wire wound on mica strips in the

known manner preferably narrow in comparison with their length, and these strips are securely held in two metal end pieces 55 or lugs 7 which form the terminals of the elements. The element wire is preferably continuous throughout but may be arranged in sections adapted for joining together. The elements with their metal end pieces 60 form a complete unit which can be easily replaced in case of breakdown. The end pieces are fixed to the base by means of long metal screws or bolts which project through the base into the hollow space 65 therein and form the main terminals 5 of the apparatus, to which terminals a pair of flexible cables 4 is connected.

A piece of sheet asbestos 8 or other fire-proof and insulating material is placed between the elements and the base.

The metal cover 3 which may be provided with holes for ventilating purposes is of pressed or spun metal and performs the dual function of a mechanical protection for the elements and a support or holder for the vessels or appliances to be heated by means of the cup-shaped cavity which can also contain the vaporising chemicals. This cavity is arranged immediately above the elements so that very little heat is lost in transmission from the elements to the liquid in the cavity. In order to prevent such loss more effectually, the elements may be disposed concentrically 85 with and under the cavity i. e. they may be bent into cup-shaped form so that all parts of the heating elements may be as close as possible to the under side of the cavity.

I claim—

An electric heating appliance consisting of a base, upright conductor legs on the upper side of said base, terminal elements for the line wires and constituting means for fastening the conductor legs to the base, 95 the binding ends of said terminals being disposed on the base, resistance heating elements detachably secured to the upper ends of said conductor legs, and a metal cover having a cup-like depression therein overlying said resistance heating elements.

In testimony whereof I have affixed my signature.

CHARLES HOWARD WALTER MORRISON.
